UNITED STATES PATENT OFFICE

CLAUDE C. SHAW, OF CAMDEN, SOUTH CAROLINA

ROCKER-SHAFT BEARING FOR LOOMS

Application filed February 5, 1931. Serial No. 513,709.

The object of this invention is to provide a simple and inexpensive rocker-shaft bearing for looms that may be substituted for the old, original bearings when the same become so worn as to require renewal, as more fully hereinafter set forth. Referring to the drawing annexed;

Fig. 1 is a perspective view of one of my bearings;

Fig. 2 is a vertical sectional view thereof; and

Fig. 3 is a longitudinal section taken through the supporting beam or girt of the loom.

Referring to the drawing by reference characters, 5 designates the usual beam or girt of the loom, and 6 a top pocket plate adjustably secured to the upper face of the girt by means of one or more bolts 7 which pass through transverse slots 8 in plate 6 and longitudinal slots 9 in the girt, these bolts and slots permitting the plate 6 to be adjustable longitudinally and transversely on the girt.

The front edge of the plate 6 is provided with an integral depending front plate 10 which is braced to the plate 6 by side flanges 11 and is provided with a pair of vertical slots 12 open at their lower ends. This plate 6 is also provided with a depending plate 13 whose lower edge is turned backwardly so as to engage under the front edge of the girt 5 to thereby assist in locking the hanger structure 6—10 to the girt.

Secured by a pair of bolts 15 to the front face of the depending plate 10 is a bearing-plate 16 which is provided at its lower end with a closed cylindrical bearing 17 for the rocker-shaft (not shown), this bearing 17 being aligned with a bushing 18, preferably made of wood. The bolts 15 pass through holes in the plate 16 and through the aforesaid vertical slots 12 in the hanger-plate 10, to thereby enable the bearing-plate 16 to be vertically adjusted. The bearing-plate is provided with a rearwardly extending rib 19 which fits in one of the slots 12 to thereby prevent lateral vibration or movement of the bearing-plate 16. To nicely adjust the bearing-plate 16 up and down, I provide its upper end with a rearwardly extending flange 20

and provide the same with a set bolt 21 which is locked in its adjusted position by a lock-nut 22, the lower end of the set screw bearing against the top face of the plate 6. In this construction it will be observed that this substitute rocker-shaft bearing may be readily attached to the regular cross-beam loom at any point in its length and that it may be used in pairs to provide proper journals for the opposite ends of the rocker-shaft, which shaft may be shortened in view of the fact that these bearings need not be affixed to the side frame in the loom. In view of the ease with which these bearings may be substituted for the old bearings, very little loss of production of the loom is suffered by their substitution for the old bearings. They in fact also afford a more substantial bearing for the rocker-shaft in view of the fact that they may be placed closer to the lay. They also have the advantage that they hold the lay in proper position and thus help other parts of the loom to function better, thus greatly reducing possibilities of mis-picks, thin places and "smashes", which of course are very detrimental in the woven product. In my improved bearings, broken swords can be readily replaced in much less time than has heretofore been possible.

I claim:

In a bearing for loom rocker-shafts, a supporting structure embodying a top plate with means for adjustably but rigidly attaching it to a loom girt or beam and a depending face plate provided with a pair of vertical open slots, a hanger-plate having a rocker-shaft bearing projecting from its front face with a lug projecting rearwardly and fitting in one of the aforesaid slots in the face plate, and bolts extending through the hanger plate and the slots in the face plate at a point above the aforesaid lug.

In testimony whereof I hereunto affix my signature.

CLAUDE C. SHAW. 95
